(57) **CLAIM**

We claim the ornamental design for an electronic device cradle for ironing board, as shown and described.

DESCRIPTION

FIG. 1 is a perspective view of an electronic device cradle for ironing board showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state of use thereof. The broken lines shown in FIG. 3 depict portions of the electronic device cradle for ironing board that form no part

(Continued)

of the claimed design. The broken lines shown in FIG. 8 illustrate environmental condition only and form no part of the claimed design.
